UNITED STATES PATENT OFFICE.

HANS WILHELM CHRISTIAN SCHRÖDER, OF LUBECK, GERMANY, ASSIGNOR TO ALEXANDER BERNHARD DRÄGER, OF FINKENBERG, LUBECK, GERMANY.

PROTECTIVE DEVICE FOR AUTOGENOUS APPARATUS.

Application filed August 18, 1921. Serial No. 493,484.

To all whom it may concern:

Be it known that I, HANS WILHELM CHRISTIAN SCHRÖDER, a German citizen, residing at Lubeck, Germany, have invented certain new and useful Improvements in Protective Devices for Autogenous Apparatus (for which I have filed an application in Germany May 2, 1918, which resulted in useful Design Patent No. 720,304, registered October 18, 1919), of which the following is a specification.

In using autogenous apparatus for welding and cutting metals which are worked by different kinds of gases, e. g. oxygen and another combustible gas, explosions of the steel cylinders or steel containers, and of the fittings attached thereto frequently occur. The cause of such explosions can only be ascribed to the fact that owing to the choking up of the mouthpiece of the autogenous burner, one of the gases passes over into the supply pipe for the other gas and consequently there is formed in this supply pipe under some circumstances as far as the steel cylinder, a dangerous mixture of the gases. Or such dangerous mixture may be already present in the steel cylinder owing to the latter having been wrongly filled with the result that the mixture is passed out into the supply pipe leading to the burner. If under such circumstances the flame of the burner strikes back, the mixed gas present in the supply pipe will become ignited with the result that in most cases an explosion in the piping or in the steel cylinder follows.

The object of the present invention therefore is to provide a protective device or cartridge by means of which all the disadvantages above mentioned are avoided. This is attained by interposing in the gas pipe a non-return valve and between the latter and the burner, in addition to the non-return valve, an explosion resistance in the form of a plate or disc of a fireproof material such as sandstone, earthenware, fire clay, magnesium oxide, or the like, which, when the flame burns inwards, does not fuse or sinter, and so stops the explosion wave. And with this end in view my invention consists in certain novel features of construction and combinations of parts as will be hereinafter described and pointed out in the claims with reference to the accompanying

sheet of drawings in which is shown an example of the invention. 55

Figure 1 shows in elevation an oxy-hydrogen welding apparatus fitted up according to the present invention and

Figure 2 is a longitudinal section, on a larger scale, of a protective cartridge constructed according to this invention and inserted in each of the two gas supply pipes. 60

Like reference letters indicate like parts.

As shown in Figure 1 the welding apparatus consists of an oxygen cylinder *a* and a hydrogen cylinder *a'* each being provided with a pressure reducing valve *b* and *b'* respectively, a protective device *c* and *c'* and a flexible pipe *d* and *d'*, both of which lead to a welding burner *e*. In this latter there takes place, in a special mixing chamber in front of the outlet opening of the mouthpiece, a mixture of oxygen and the other combustible gas, which in this case is hydrogen. Now if while the apparatus is being used, the opening of the mouthpiece of the burner becomes wholly or partially choked up owing to the entrance of dirt or liquid metal, a mixture of the two gases may pass into one or other of the two supply pipes *d* or *d'*, the gas which is under the higher pressure passing over into the supply pipe for the gas which is under the lower pressure. According to the magnitude of the difference between the pressures this mixed gas will flow back into the pressure reducing valve appertaining to the said supply pipe and even on into the steel cylinder. Under such conditions, if the flame should strike back in the burner, the mixed gas in the supply pipe will be exploded, and if any of said mixed gas is present in the pressure reducing valve and the steel cylinder, the contents of the latter also, will be caused to explode. 90

In order to keep any mixed gas which may have been formed, away from the corresponding pressure reducing valve and steel cylinder, and to intercept and render harmless explosion waves of this mixed gas resulting from the striking back of the flame from the burner, there is located in each gas supply pipe, a protective apparatus or cartridge *c* and *c'*, the cartridge, in each instance, is preferably positioned between the supply pipe *d* or *d'* and the pressure 95 100 105

reducing valve b or b^1 respectively, and is therefore always located upon the low pressure side of the reducing valve. As the structural form of both the cartridges 5 c and c^1 is the same, the illustration and description of only one of the same e. g., the cartridge c^1 will suffice for the comprehension of the invention. This device consists of a cup-shaped cartridge case c^1 , see 10 Figure 2, provided with a non-return valve f , acted upon by a spring f^1 , and a connecting screw thread g in the gas inlet nozzle h , a sleeve i containing a porous fire-proof protective disc k of magnesium oxide 15 inserted gas-tight therein, and a cartridge cover m with a connecting screw thread n on the cup shaped gas outlet nozzle o . By screwing the parts c^1 and m together the protective disc i , k , is clamped firmly and 20 the joint made gas-tight by the interposition of annular packing discs or washers l , so that all the gas which passes through the pipe and the protective cartridge is compelled to pass through the protective 25 disc or plate k , which as regards its porosity, is of such a nature that it allows gas to pass through it in both directions. The gas when flowing in the right direction opens the non-return valve f and then flows 30 through the protective plate k to the burner. Any gaseous mixture passing back in the reverse direction through the protective plate is however immediately stopped by the non-return valve f which automatically 35 closes and cuts off the mixture so that it cannot get into the pressure reducing valve and the steel cylinder. Furthermore the protective plate k stops any explosion wave coming from the burner on its front 40 surface, so that the non-return valve is not touched by the explosion wave and if any mixed gas should be contained in the pressure reducing valve and the steel cylinder this gas cannot be ignited. The flame on 45 the contrary goes on burning at the front face of the protective plate until the mixed gas present has burned out or until the stop valve of the pressure reducing valve is closed. 50 Without the non-return valve f the protective plate k would, as can be seen, afford no perfect safeguard against the penetration of the gas mixture into the pressure reducing valve and the steel cylinder, and 55 on the subsequent use of this cylinder for other purposes an accident might easily happen. The combined provision of a non-return valve and of a protective plate which stops the explosion wave and is composed 60 of porous, fireproof material, such for example as magnesium oxide, sandstone, or the like, offers the greatest protection

against the dangerous effects of the backward flow of the gas, formation of mixed gas and striking back of the flame. 65

The manufacture of the protective discs or plates may be conveniently carried out by moulding the plates from a mixture of granulated fireproof material such as sandstone, magnesium oxide, fire clay, etc. and 70 granulated combustible material, e. g. coal dust, or the like, and then afterwards burning them. By so treating the plates thus prepared the combustible material burns away, and thus the necessary porosity is 75 provided which latter can be regulated by the proportion selected for the mixture.

The increased resistance which is naturally produced by the non-return valve and the porous protective plate, but which is 80 in itself very small, can be easily overcome by a moderate increase in the pressure of the oxygen and also of the hydrogen. Protective plates which become defective can be easily replaced by spare plates. 85

It is preferable to provide such a protective cartridge for each of the two gas pipes d and d^1 , but in any case one should be provided for the pipe which supplies the gas at the lower working pressure. Instead 90 of being placed on the pressure reducing valve the protective cartridge may be placed on the burner. It may also be made in two parts and the part which contains the protective plate mounted on the burner and the 95 part which contains the non-return valve on the pressure reducing valve.

I claim:

1. A protective device of the kind described comprising an inlet nozzle, a cup-shaped case at the outlet end thereof and comprising an integral part of said nozzle, a non-return valve in said inlet nozzle between its ends, an outlet nozzle detachably connected with said case, and a flame-arresting disc clamped in said case by said outlet nozzle and obstructing the axial passage through said device. 100

2. A protective device of the kind described comprising an inlet nozzle, a cup-shaped case at the outlet end thereof and comprising an integral part of said nozzle, a non-return valve in said inlet nozzle between its ends an outlet nozzle detachably connected with said case, a sleeve clamped in said case by said cup-shaped outlet nozzle, and a porous disc of fire-proof material fixed in said sleeve and obstructing the axial passage through said device. 110 105 115

HANS WILHELM CHRISTIAN SCHRÖDER.
